2,033,676

SAFE EDGE CUP FOR IMMERSION ROLLS IN
FILM COATING MACHINESNorman F. Beach, Rochester, N. Y., assignor to
Eastman Kodak Company, Rochester, N. Y., a
corporation of New York

Application June 19, 1935, Serial No. 27,406

9 Claims. (Cl. 91—46)

My invention relates to photography and more particularly to means for preventing the coating material in a film coating machine from wetting the surface of the immersing roll or 5 the reverse side of the strip to be coated.

In the productions of sheet materials of many forms, such as photographic film, transparent wrapping material, paper, and artificial leather, by way of example, it is often found necessary 10 or desirable to treat the surface of the sheet with a liquid agent, in order to either leave a deposit on the sheet by the evaporation, setting, or congealing of the liquid, or simply to alter the character of the surface by the action of 15 solvents or chemical agents. Several means or methods of applying the liquid to the sheet are available, in the majority of which the moving sheet material is brought into contact with the liquid for as long a time as may be feasible, 20 after which the continued or continuous motion brings the sheet out of contact with the liquid.

The particular means of application to which my invention refers, is that in which the moving sheet or film passes around the surface of a roll, 25 the periphery of which may or may not move at the same rate of speed as the film, and while in contact with the roll dips to a greater or less extent below the surface of the liquid coating material, which is contained in a suitable 30 vessel.

In such a process, which may be called the immersion process of coating, it is frequently necessary or desirable to prevent any of the coating material from coming in contact with 35 the reverse side of the sheet or film, or with the surface of the immersion roll. And at the present time this difficulty is eliminated by the use of safe edge cups which are provided with safe edge ring inserts which are fitted to ride on the 40 web material on the periphery of the immersion roll, the liquid tight joint being maintained by an excessive pressure applied to the safe edge ring insert. This method of providing a liquid tight joint on immersion rolls of a coating machine has proved unsatisfactory, because due 45 to the excessive pressure and subsequent frictional wear to which the safe edge ring insert is subjected, it has been found very difficult to maintain a perfect fit between the safe edge ring insert and the periphery of the roll; without which a liquid tight joint is impossible.

Therefore, one object of my invention is to provide suitable safe edge cups which are designed to cooperate with the ends of the immersion roll in a web coating machine to prevent

any of the coating material from wetting the reverse side of the web to be coated or wetting the surface of the immersion roll. Another object is to provide safe edge cups which are adapted to form liquid tight joints between the 5 ends of the immersion roll and that portion of the immersion roll contacting the coating material wherein frictional wear of the safe edge cups is reduced to a minimum without loss of efficiency. And still another object is to provide safe edge cups for an immersion roll which are adapted to be installed on any coating machine of this type without excessive additional expense. And another object of my invention is to provide a safe edge cup whose efficiency 10 does not depend upon an exacting fit or excessive pressure, the elimination of these two factors greatly lengthening the useful life of the 15 safe edge cups.

Briefly, my invention consists of an ordinary 20 immersion roll whose surface is provided with grooves adjacent its two ends. These grooves are so spaced apart that the web of material to be coated has a width sufficient to overlap and extend a slight distance beyond them. The 25 ends of the immersion roll are confined by safe edge cups one wall of which conforms in shape to that of the immersion roll and acts as a lip or insert ring to press against the web of material on the roll opposite the grooves therein, 30 and depress a small area of the web into said groove to provide a liquid tight joint. A tank containing the coating material is adjustably mounted so that the coating material therein can be brought into contact with the web material 35 on the immersion roll. When this tank is in the proper immersing position, that portion of the web between the grooves in the immersion roll is properly coated while the ends of the immersion roll and the reverse side 40 of the web are prevented from becoming wet by virtue of the liquid tight joint formed by depression of the web into the grooves on the surface of the immersion roller and the confining action of the other walls of the safe edge cups. 45

The novel features that I consider characteristic of my invention are set forth with particularity in the appended claims. The invention itself, however, both as to its organization and its method of operation, together with additional objects and advantages thereof, will best be understood from the following description of specific embodiments when read in connection with the accompanying drawing in which,

Fig. 1 is a broken front view of the combination, 55

partly in elevation and partly in section to most clearly illustrate the function and construction of the safe edge cups, and Fig. 2 is an end view of the combination with the extraneous parts omitted and the tank cut away to show the relative positions of the immersion roll and the safe edge cup in operating position, and to show one way of adjustably mounting the safe edge cup relative to the immersion roll.

10 Like references refer to corresponding parts in both figures.

As shown in Fig. 1, the immersion roll 3 is mounted to rotate in bearings 4 and be driven by any suitable means not shown. The surface 15 of the immersion roll 3 is cut to provide the fillets or grooves 5 which are located adjacent the ends of the roll 3 and which are so located on the surface of the roll 3 that the web of material F to be coated completely overlaps them 20 and extends beyond them a substantial distance as shown at 6. The lower portion of the ends of the immersion roll 3 are encased by the safe edge cups 7 which are semi-circular in shape and whose depth is sufficient to receive the 25 lower portion of the immersion roll 3. One wall 8 of the safe edge cup 7 is straight across the top and completely covers the lower portion of the end of the roll 3, but the other vertical wall 9 of the safe edge cup 7 is curved to 30 form to the shape of the roll 3 and acts as a lip or ring insert 10 to contact the web material F on the roller opposite the grooves 5 and subsequently depress a small area of the web F into the groove as shown at 11 thereby forming 35 a liquid tight joint to prevent the passage of the coating material to the surface of the roll or to the reverse side of the web F. The safe edge cups 7 may be adjustably mounted, as shown in Fig. 2, by providing them with an arm 40 12, which is shown as an integral part, pivoted to the frame at 13 so that it can be raised or lowered relative to said roll 3 by any suitably adjusting screw 14, the purpose of which will be explained hereinafter.

45 A tank 15 containing the coating material L is adjustably mounted relative to the immersion roll 3 so that it can be brought into contact with said immersion roll or removed therefrom to permit the roll 3 to be threaded with the web F. For the purpose of illustration I have shown the tank 15 provided near each end with a rack 16 which is slidable in guides 17 and engaged by a pair of pinions 18 which are mounted on a shaft 19 journaled in bearings 20 and controlled 50 by the operating handle 21. In immersing position, the top of the tank 15 is substantially below the open end of the safe edge cups 7 so that any overflow which might occur in the tank 15 will not enter the safe edge cups 7. The 55 bottom of the reservoir portion 22 of the safe edge cup 7 is designed to be well below the bottom of the immersion roll 3, so that in case there may be a slight accidental leak of the coating material through the joint formed between the groove 5 in the roll 3 and the lip 10 of the safe edge cup 7 in conjunction with the web F preliminary to proper adjustment, it could be accumulated in the bottom of the safe edge cup 7 without coming in contact with the 60 end of the roll 3 or the edge of the web material F.

In order that the adjustment of the two safe edge cups 7 relative to the immersion roll may be made equal and simultaneous, a bar, not 65 shown, connecting the two arms 12 may be pro-

vided for, and any adjustable means such as an adjusting screw 14 provided to act on said connecting bar. Also, my showing of the tank containing the coating liquid being adjustable by rack and pinion is merely for illustrative purposes, and it is obvious that this method of adjustment could be supplemented by any number of forms without deviating from the spirit of my invention.

In my disclosure I have shown one wall 8 of the safe edge cups adapted to act as a lip or an insert ring 10 for depressing the web F into the groove 5 of the immersion roll, but by way of modification I could provide a removable insert ring which could be removably mounted in 15 said safe edge cup so that it could be independently adjusted or replaced if need be.

To initially thread the immersion roll 3 with the web F and prepare for subsequent operation the following procedure is followed. First, 20 the tank 15 for containing the coating liquid is lowered from the immersion roll 3 by operating the control handle 21. After the tank 15 has been lowered, the safe edge cups 7 can be lowered from contact with the immersion roll 25 3 by proper adjustment of the adjusting screw 14. With the tank 15 and the safe edge cups 7 lowered from said immersion roll 3, ample space is provided so that the web F can be threaded around the bottom of the roll and 30 properly positioned to overlap the grooves 5 in the immersion roll 3, in the illustrated manner. After the roll is properly threaded with the web F, the safe edge cups 7 are brought back into the position shown in Fig. 1 and adjusted so 35 that the lips 10 of said cups contact the web F with sufficient pressure to depress a small area of said web F into the grooves 5 to effect a liquid tight joint. The tank 15 after being properly filled with the coating liquid is then 40 raised into position under the immersion roll 3 so that the level of the coating liquid is well above the bottom of the roll to effect an immersion thereof, but at the same time said liquid level is below the top of the safe edge cups 7 so 45 that no overflow is possible. By referring to the drawing, it can be seen that this relative position of parts provides for a proper immersion of that portion of the web F that lies on the bottom of the roll between the lips or insert rings 10 of the safe edge cups 7. And by virtue of the 50 safe edge cups 7 and their cooperation with the grooves 5 in the roll 3, no coating liquid is allowed to wet the end of the roll 3 or the reverse side of the web F.

This method of making a liquid tight joint between the central portion of an immersion roll and its ends has the advantage that the grooves 5 enable a satisfactory liquid tight joint to be formed without, however, the necessity of 55 exerting as much pressure on the material of the web as would have to be exerted if the joint were merely formed by pressing the web against the unbroken surface of the roll 3. The ultimate result obtained by this new construction provides for a great reduction in frictional wear 60 formerly incurred by the lip or insert ring 10 of the safe edge cup 7, and this reduction greatly prolongs the life of the frictionally engaging parts and provides for a more efficient liquid 65 tight joint with need for fewer replacements or adjustments. The groove 5 itself may have any shape or depth which is found to be most efficient for the web material employed. I do not 70 regard the arc upon which the safe edge cup 75

7 is formed as essential, but it may be any size as dictated by the directions at which the web F approaches and recedes from the immersion roll 3, and by the readiness with which it would be necessary to remove the safe edge cup 7 from the operating position.

Although I have shown and described certain specific embodiments of my invention, I am fully aware that many modifications thereof are possible. My invention, therefore, is not to be restricted except in so far as is necessitated by the prior art and by the spirit of the appended claims.

Having thus described my invention, what I claim is new and desire to secure by Letters Patent of the United States is:

1. In a web coating machine the combination with an immersion roll for the web to be coated, said roll provided with grooves near its ends which are adapted to be covered by overlapping portions of the web to be coated, of a tank containing the coating material adjustably mounted relative to said immersion roll for regulating the extent of immersion of the web material on said immersion roll, and suitable means adjustably mounted relative to said roll for encasing the ends of said roll and depressing a small area of said web material into the grooves in said roll to form liquid tight joints between the center of said roll and its ends.

2. In a web coating machine the combination of an immersion roll for the web to be coated, said roll provided with grooves near its ends which are adapted to be covered by overlapping portions of the web to be coated, of suitable means for encasing the ends of said immersion roll and depressing the web material into said grooves in said immersion roll to form a liquid tight joint, and a tank containing the coating material, said tank adjustably mounted relative to said roll to bring the coating material into contact with the unprotected portion of said immersion roll and its contacting web of material.

3. In a web coating machine the combination of an immersion roll for the web to be coated, said roll provided with grooves near its ends adapted to be covered by overlapping portions of said web, of safe edge cups adjustably mounted relative to said immersion roll for confining the ends thereof, means associated with said safe edge cups for depressing a small area of said web into the grooves in said roll to effect a liquid tight joint, and a tank containing the coating liquid said tank being adjustably mounted relative to said immersion roll for bringing the coating liquid into contact with the bottom of said roll.

4. In a web coating machine the combination with an immersion roll for the web to be coated, said immersion roll provided with grooves near its ends adapted to be covered by overlapping portions of said web material, of a tank for containing the coating material and adjustably mounted relative to said immersion roll, and suitable means for preventing the coating material from coming in contact with the surface of the roll or the back of the web material, said means including a pair of cup members for encasing the ends of said roll and provided with a lip for depressing the web material into the grooves in said immersion roll to form a liquid tight joint between the center of said roll and its ends.

5. In a web coating machine the combination

with an immersion roll for the web to be coated, said roll provided with grooves near its ends adapted to be covered by overlapping portions of said web of material, of a pair of safe edge cups encasing the lower portion of each end of said immersion roll and adjustably mounted relative to said roll, one wall of each of said safe edge cups providing a lip to engage the web opposite the grooves in the immersion roll, said engagement depressing a small area of the web into said grooves to form liquid tight joints therebetween, and a tank containing the coating material said tank confining the lower portion of the immersion roll and the safe edge cups, the level of the coating material in said tank allowing for the immersion of the lower part of said roll and the web contacting it save that portion which is protected by said safe edge cups.

6. In a web coating machine the combination of an immersion roll for the web of material to be coated, the periphery of said roll near its ends provided with grooves adapted to be covered by an overlapped portion of the web material contacting said immersion roll, safe edge cups adjustably mounted relative to said immersion roll and encasing the lower portions thereof at its ends, one wall of each cup providing a lip for engaging the web material opposite said groove in said roll, depressing said web material therein to form a liquid tight joint, and a tank for said coating material adjustably mounted relative to said immersion roll to bring said coating material therein in contact with that portion of the web material on said roll which is not protected by said safe edge cups.

7. In a web coating machine the combination of an immersion roll for the web to be coated, the surface of said roll provided with grooves which are positioned so as to be overlapped by the web material contacting said roll, safe edge cups encasing the lower portion of said roll at each end and adjustably mounted relative to said roll, one wall of each of said safe edge cups conforming in shape to the surface of said roll and providing a lip for engaging the web material opposite the grooves in said roller, said engagement depressing the web material into said groove to provide a liquid tight joint between the middle and ends of said roll, and a tank containing the coating material for said web, said tank adjustably mounted relative to said roll for bringing the coating material therein in contact with the lower edge of said roll between said safe edge cups.

8. In a web coating machine the combination with an immersion roll for carrying a web of material to be coated, said roll provided with grooves near its ends adapted to be covered by an overlapping portion of said web material, of safe edge cups encasing the lower portion of said roll at its ends, one wall of each of said safe cups being circular in shape to conform to the surface of said roll and act as a lip for engaging the web material on said roll opposite the grooves in said roll, said engagement causing said web material to be depressed into said grooves to form a liquid tight joint, suitable means for adjustably mounting said safe edge cups relative to said roll for regulating the contact between said safe edge cups and said web on said immersion roll, and a tank containing the coating material adjustably mounted relative to said immersion roll to bring said coating material into contact with that portion of

the roll and web material thereon not protected by said safe edge cups.

9. In a web coating machine the combination of an immersion roll for the web to be coated, the surface of said immersion roll provided with grooves so spaced on said roll as to be overlapped by edges of the web contacting said roll to be immersed, safe edge cups encasing the lower portion of each end of said immersion roll, said safe edge cups provided with arms which are pivotally mounted adjacent said roll to allow said safe edge cups to swing into and out of contact with said roll, and an adjusting screw bearing on said arm for adjusting the

position of said safe edge cups, the bottom of said safe edge cups extending longitudinally of the bottom of said roll and provided with a projecting lip for engaging the web material on said immersion roll opposite the grooves in said roll when brought in contact therewith said engagement depressing the web material into said grooves to provide a liquid tight joint therebetween, and a tank for containing the coating material said tank being adjustable relative to 10 said immersion roll for bringing the coating material in contact with the immersion roll between the safe edge cups.

NORMAN F. BEACH.
